CLAIM

The ornamental design for a multi-position multi-object organizer stand, as shown and described.

DESCRIPTION

FIG. 1 is a front perspective view of a multi-position multi-object organizer stand in accordance with the invention;

FIG. 2 is a rear perspective view of FIG. 1;

FIG. 3 is a front elevation view of FIG. 1;

FIG. 4 is a rear elevation view of FIG. 1;

FIG. 5 is a left elevation view of FIG. 1;

FIG. 6 is a right elevation view of FIG. 1;

FIG. 7 is a top plan view of FIG. 1; and,

FIG. 8 is a bottom plan view thereof.

The broken lines illustrate portions of the article that form no part of the claimed design.
